UNITED STATES PATENT OFFICE.

EDWARD J. WALL, OF CAMBRIDGE, MASSACHUSETTS, ASSIGNOR TO KALMUS, COM-
STOCK & WESTCOTT, INC., OF BOSTON, MASSACHUSETTS, A CORPORATION OF
MASSACHUSETTS.

METHOD OF REFINING CACAO-OIL.

1,386,476.

Specification of Letters Patent.

Patented Aug. 2, 1921.

No Drawing.

Application filed July 15, 1919. Serial No. 311,054.

To all whom it may concern:

Be it known that I, EDWARD J. WALL, a subject of the King of the United Kingdom of Great Britain and Ireland, residing at 5 Cambridge, in the county of Middlesex and State of Massachusetts, have invented certain new and useful Improvements in Methods of Refining Cacao-Oil; and I do hereby declare the following to be a full, clear, and 10 exact description of the invention, such as will enable others skilled in the art to which it appertains to make and use the same.

The present invention relates to an improved method of refining cacao oil. In extracting chocolate from the cacao bean after the roasting, crushing and filtering operations, the oil which runs off from the filter press, known as cacao oil or cacao butter, consists of a mixture of glycerids of 15 stearic, palmitic and arachidic acids containing chocolate in suspension, and certain volatile substances which give it its characteristic odor and taste. The chocolate in suspension is removed by filtering through paper or cloth in the usual manner, keeping the temperature above the melting point. The removal, however, of the volatile substances which still confer upon the oil the odor and taste of chocolate is a matter of 20 difficulty, and it is necessary that the constitution and physical characteristics of the oil remain unchanged. One of the uses to which the refined oil is especially adapted is the manufacture of margarin. The object of this invention is to produce a method 25 of refining cacao oil, particularly the method by which the volatile odorous and gustable ingredients of the oil may be removed without injury to the constitution of the oil. To 30 this end the invention consists in the method of refining cacao oil hereinafter described and particularly defined in the claims. The cacao oil, as it comes from the chocolate manufacturers, is first filtered in the 35 usual manner to remove the solid chocolate constituent by filtering it through paper or cloth and keeping the temperature above melting point.

The volatile, gustable and odorous ingredients of the oil are numerous complicated substances which are present in small

percentages, and are all characterized by their volatility. According to the present invention, these substances are removed or characteristically changed by exposing the 55 oil to the action of ultra-violet light. To this end the oil is spread in shallow pans in thin layers in a liquid state at a temperature near its melting point and is exposed to the light from a quartz mercury vapor lamp 60 for a period of time sufficient to remove the volatile odorous and gustable ingredients. The oil is liquefied so as to be more transparent and in order that currents in the oil may cause all the parts of the oil to be exposed to the light. The depth of the oil in the pans is made about $\frac{1}{4}$ inch so that the lower layers of the oil will not be unduly deprived of the light by passage through a considerable thickness of the oil. The temperature should be retained as near as possible to the melting point as the tendency to deterioration of the oil is greater the higher the temperature. While a quartz lamp is preferred because it is less opaque to ultra- 65 violet rays than common glass, certain glasses may be used without great loss of efficiency in the working of the process. Where layers of cacao oil $\frac{1}{2}$ inch in thickness are employed and the light is at a distance of 4 inches, the operation will be completed at the end of 14 hours. With greater thicknesses a longer duration of the light 70 will be required. The product of the process is refined cacao oil entirely deprived of 75 its former characteristic chocolate flavor. It has, however, the bland oleaginous odor and taste of an oil. This odor and taste is comparatively faint and tenuous and is wholly unobjectionable in many uses, and 80 particularly when the oil is used as an ingredient of margarin, as the ingredients which confer the odor and taste of butter are sufficiently vigorous and pervasive to characterize the odor and taste of the product. The product is substantially deprived 85 of its characteristic deep yellow color by the operation of the ultra violet light. 90

Having thus described the invention, what 95 is claimed is:—

1. The method of refining cacao oil containing volatile gustable and odorous sub- 100

stances which consists in exposing it in thin layers in a liquid state at a temperature near its melting point to ultra violet rays for a period of time sufficient to destroy some of the gustable and odorous substances.

2. The method of destroying the objectionable taste and odor of cacao oil which

consists in subjecting the oil in a liquid state to the action of ultra violet rays.

3. The method of destroying the objectionable taste and odor of cacao oil which consists in subjecting the oil to the action of ultra violet rays.

EDWARD J. WALL.
